UNITED STATES PATENT OFFICE

1,953,569

APPARATUS FOR APPLYING WATERPROOF BANDS FOR GLAZING AND THE LIKE

Léon Joseph Sagit, Paris, France, assignor to Paix & Cie, Douai, Nord, France, a French company

Application February 10, 1932, Serial No. 592,091
In France March 17, 1931

6 Claims. (Cl. 18—3.5)

In the construction of glazed roofs (sheds) for instance, in order to obtain a waterproof joint between the glass panes and their supports or frames, it is known to cover the joint with a waterproof band consisting of cloth or other bands coated with layers of bitumen or analogous material. Hitherto such bands have been put in place by hand. The band is first softened by heating it by means of a soldering lamp or a blow-pipe, and the workman then applies the band by hand, causing it to assume the proper shape by pressing it with the fingers. For this reason, the work is long and expensive, and the appearance is unattractive, especially when the bitumen melts by an excessive heating and thus flows upon the glass panes.

In other cases, bands are applied by the use of an adhesive substance which is coated on by a brush according as the band is applied. The present invention relates to an apparatus for applying waterproof bands for glazing and analogous works, which is chiefly characterized by the fact that it comprises one or more bending members fixed or rotatable, of a suitable shape, and assuming such positions that the band will be properly bent and applied against the surfaces of the support such as a T-iron bar or the like.

According to another feature, the apparatus comprises a roller or a similar member which serves to support the band and which is mounted in front of the said bending members in the direction of travel of the apparatus and is adapted to form in said band an inclined sheet which may be readily heated or coated with an adhesive substance before it is applied.

In the accompanying drawings which are given by way of example:

Fig. 1 is an elevational view of the apparatus,
Fig. 2 is a section on the line 2—2 of Fig. 1,
Fig. 3 is a sectional end view of the apparatus,
Fig. 4 is a partial section on the line 4—4 of Fig. 2,
Fig. 5 is an end view of a bending member, according to another construction,

Fig. 6 is a front view of the same,

Fig. 7 is a section on the line 7—7 of Fig. 6.

In the form of construction shown in Figs. 1 to 4, the apparatus consists of a frame 1 upon which is mounted a curved member 2, screwed to said frame or formed in one therewith; in the middle of said curved member is situated a rod 3 upon which is fitted a handle 4.

The frame 1 rests upon two tubes 5 formed in one with the frame. At respective ends of said

tubes are mounted two screws 6 (or like adjustable device) whose heads rest directly upon the glass panes 7. Two cylindrical arms 8 extend forwardly of the frame 1.

Below the said frame are situated two bending members, such as rollers 9, having a suitable form so as to fit into the angle between the web of the T-iron bar 10 (or the like) supporting the glass panes 7, and the panes themselves. Each roller is mounted on an axle 11 which is screwed into one of the bossages 12 of the said frame; the rollers are held upon their axles 11 by a respective wing nut 13 screwed upon a threaded sleeve 14, or by like means.

The two axes 11 intersect, the angle Z between them (Fig. 2) being of 90 degrees in the present example; this angle may obviously vary according to the shape of the iron bar or other support.

Preferably, every axle is not situated in a transverse plane, such as the plane of Fig. 2. It is inclined from this plane by a small angle y (Fig. 1) which may for instance be 5 degrees, the inclination being directed upwardly from front to rear of the plane of Fig. 2.

The cylindrical arms 8 (Fig. 1) carry two collars 15 which may be secured to the said arms by a set-screw 16. At the top of said collars is mounted a threaded pin 17.

A roller 18 of suitable shape is screwed to the central part of the pin 17 and is held in this position by a pair of lock-nuts 19. On either side of the roller 18, a respective end-plate 20 is screwed to the pin 17. Each plate is held in position by a lock-nut 21 for example. On the smooth parts 22 of the threaded pin are pivotally mounted two arms 23. At their opposite ends, the said arms 23 (Figs. 1 and 2) are screwed to the two threaded ends 24 of the smooth axle 25.

This axle 25 connected by springs 26 with the frame 1, carries at its middle part a roller 27 held in place for instance by two rings 28 fastened by pins. On either side of the roller 27, the axle 28 carries two respective end-plates 29 whose lower ends are adapted to rest upon the frame 1, and whose position can be adjusted by two set-screws 30, or otherwise.

On the ends of the arms 8 (Fig. 1) are mounted collars 31 whose position can be adjusted by set-screws 32 or otherwise. The collars carry a roller 33 which is pivotally mounted on the axle 34. This roller is grooved so as to roll upon the web of the T-iron bar 10.

To one of the arms 8 is secured in any suitable manner, for instance by an upright 35 and a collar 36 a receptacle 37 (Fig. 3). This receptacle

is provided at the top with a pressure pump 38 and is connected by a tube 39 fitted with a cock 40 with one or more blowpipes 41 which can be regulated by milled wheels 42. The blowpipe or blowpipes are held by a collar 43 secured to the receptacle 37. The said receptacle can be removed by means of a handle 44 secured to the same.

The operation is as follows: The apparatus is placed upon the glass panes 7 by means of the tubes 5, and the roller 33 rests at the front part upon the web of the T-iron bar 10. The end of a waterproofing band is inserted into the apparatus in the following manner. The end-plates 29 are first adjusted according to the width of the band in use. These plates are then fixed upon the axle 25 by the set-screws 30. The same operation is performed for the end-plates 20. The band is then inserted below the stretching roller 27 (Figure 4), after that upon the intermediate roller 18. The band 13 is then brought between the rollers 9.

The apparatus is moved forward in the direction of the arrow *f* while pressing downwards upon the handle 4.

The band thus travels forward, and is accurately applied to the supporting bar 10 and to the glass pane 7, by means of the bending rollers 9. Each roller 9 commences to act upon the band at a point A and leaves it at a point A'. Due to the inclination *y* of the axle 11, the roller 9 exercises a transverse traction upon the band during the whole of this period, and thus the band is exactly fitted to the supporting bar 10 and to the glass pane 7.

The roller 27 which presses upon the band permits to exercise a practically constant force upon the apparatus for the forward feed, irrespectively of the physical state of the band (whether more or less soft according to the temperature), and also to exercise a practically constant force in the direction of the arrow *f*, due to the weight of the remainder of the band to be applied, or to the resistance of the band to the forward travel.

In fact, according to the said force or to the physical state of the band, the roller 27 will rise more or less against the action of springs 26, whereby the length of the curved part will be varied.

If a band impregnated with a bituminous substance or the like is employed, this band is softened by the flame of the blowpipe or blowpipes.

Figs. 5 to 7 show a modified form of the members used for the bending of the said band, and herein the member adapted for the bending of the band 50 in order to apply it upon the inverted T-iron bar 10, or the like, consists of a metallic sheath 51 having a U-shaped cross-section, and its external and internal outline *abcdef* (Fig. 7) corresponds practically to the very section of the bar 10 which is to be covered. The inner edges 52 are preferably bevelled or rounded at the front part where the band enters, as shown in Fig. 5, so as to afford a gradual bending action upon the band 50.

The sheath 51 may consist of lead or other suitable metal, latter being preferably of a sufficiently plastic nature to avoid damage to the band.

The said sheath 51 may be properly secured to any support, for instance to the frame 1.

The fastening may be realized for instance by holding the sheath 51 in a support 53 consisting of cast or wrought iron, or like metal. The

sheath will be provided with lugs or analogous parts 54 by which it may be secured to the support.

The sheath 51 provided with its holder or support 53 may be substituted for the rollers 9, or it may be used in the same apparatus in combination with these rollers.

The aforesaid apparatus is well adapted for bands which are thin or very pliable, but which will not be softened to such a degree that they will be torn off when put in place.

The blowpipes 41 may be replaced by a spraying device by which an adhesive substance is supplied to the band.

As will be observed, the said apparatus affords the approved results, and the band is applied at a much higher rate than usual, this being at least ten times the customary speed.

Obviously, the present invention is not limited to the forms of construction herein described and represented, these being given solely by way of example.

Having now described my invention what I claim as new and desire to secure by Letters Patent is:

1. An apparatus for applying a waterproof band upon a joint, comprising means adapted to said band and to simultaneously stretch it in a transverse direction before applying it upon the corresponding joint, the operative outline of said bending means mating substantially with the outline of the adjacent parts of the joint, a band guiding member placed forwardly of the bending means in the direction of motion of the apparatus and adapted to supply the waterproof band to the bending means and to form in said band an inclined run which may be made adhesive before being applied against the joint, yielding means engaging and longitudinally stretching the waterproof band for regulating the pressure to be exercised by the operator upon the apparatus in order to move the same and to unwind the band, said apparatus being adapted to be moved along the joint in order to bend the band and apply it against said adjacent parts. 120

2. An apparatus for applying a waterproof band upon a joint, comprising means for bending said band, the operative outline of said bending means mating substantially with the outline of the adjacent parts of the joint, a band guiding member placed forwardly of the bending means in the direction of motion of the apparatus and adapted to supply the waterproof band to the bending means and to form in said band an inclined run, yielding means engaging the waterproof band for regulating the force to be exercised upon the apparatus in order to move the same and to unwind the band, a transverse rod, lateral plates adjustably mounted on said rod on either side of said bending means so as to accommodate the width of the band, said apparatus being adapted to be moved along the joint in order to bend the band and apply it against said adjacent parts. 130

3. In an apparatus as claimed in claim 2, heating means facing the adhesive side of the inclined run of the band for heating the same before the band engages said bending means. 140

4. In an apparatus as claimed in claim 2, gluing means facing the adhesive side of the inclined run of the band for applying glue to the same before the band engages said bending means. 145

5. An apparatus for applying a waterproof band upon a joint by moving along the joint in 150

order to bend the band against the adjacent parts, comprising rotary rollers for bending said band, the operative outline of said rotary rollers mating substantially with the outline of the adjacent parts of the joint, whereas the spindles 5 of said rotary rollers intersect at a point situated behind the vertical plane passing through

the points of contact of said rollers and band, so as to stretch the band transversely.

6. An apparatus according to claim 5, in which said rotary rollers have a tapered shape, said spindles being further inclined in a trans- 80
verse plane.
